UNITED STATES PATENT OFFICE.

JOSEPH B. MALYS, OF EAST YOUNGSTOWN, OHIO.

SAFETY-LOCK.

1,337,085.

Specification of Letters Patent. Patented Apr. 13, 1920.

Application filed November 5, 1918. Serial No. 261,299.

To all whom it may concern:

Be it known that I, JOSEPH B. MALYS, a citizen of Poland, and a declarant in U. S., residing at East Youngstown, in the county 5 of Mahoning and State of Ohio, have invented new and useful Improvements in Safety-Locks, of which the following is a specification.

This invention relates to locks, and has for 10 its object the provision of a lock in which the key receiving opening does not conform to the shape of the key, this lock being used in connection with a key in which the bit is pivotally connected with the shank thereof 15 so that upon insertion of the key within the key hole the bit will be automatically folded or swung into a position within the shank, a spring being provided within the shank of the key for projecting the bit into operative 20 position when the shank has been passed through the key-hole, the purpose of this construction being to prevent the taking of wax impressions from the key-hole of a lock to serve as a guide for the construction for 25 making of a false key.

An important object is the provision of a locking mechanism of this character in which the key bit is so mounted in respect to the shank that the swinging of the bit to 30 a position within the shank will be automatically effected upon insertion of the shank into the key-hole or withdrawal therefrom.

A further object is the provision of a device of this character which will be extremely simple and inexpensive in manufacture, highly efficient in use, durable in service and a general improvement in the art.

With the above and other objects and advantages in view, the invention consists in the details of construction to be hereinafter more fully described and claimed and illustrated in the accompanying drawings in which:—

45 Figure 1 is an elevation of a padlock constructed in accordance with my invention.

Fig. 2 is a side elevation of a key to be used in connection therewith, the bit of the key being in operative position,

50 Fig. 3 is a side elevation of the key with the bit swung within the shank in the position assumed when the shank is inserted through the key-hole in the pad-lock.

Fig. 4 is a similar view with the bit of the

key swung in the opposite direction as when 55 the shank is withdrawn from the key hole.

Fig. 5 is a longitudinal sectional view through the key, and

Fig. 6 is a detail cross sectional view.

Referring more particularly to the drawing the numeral 10 designates a padlock of any ordinary form and in carrying out my invention the padlock is provided with a circular key hole 11. In connection with the lock 10, I employ a key 12 comprising a 60 cylindrical shank 13 having one end provided with a handle 14 and the other recessed as shown at 15. Pivoted within the recess 15, as shown at 16, is the key bit 17 which of course has its operating end so 65 formed as to properly engage the wards within the lock. Secured within the recess 15 and bearing upon the edge of the bit 17 is a leaf spring 18 the function of which is to hold the bit 17 in a position for operative action upon the mechanism of the lock 10. The spring has a right angularly bent 70 free end 19 adapted to engage the forward edge of the bit when the bit is swung in one direction, and the spring is provided with 75 a bent portion 20 adapted to engage the rear edge of the bit. At this point, it is pointed out that the width of the bit 17 must not be greater than the diameter of the shank 13 so that when the bit 17 is swung into either of 80 the positions shown in Figs. 3 and 4 it will 85 be entirely confined within the recess 15.

In the use of my lock, and key, a shank 13 of the key is inserted through the hole 11, whereupon the bit 17 will rotate upon the 90 pivot 16 as soon as the bit 17 engages the front of the lock adjacent the opening 11. As the operator continues to push upon the shank 13, the bit 17 will be rotated to a sufficient extent to be disposed entirely within 95 the recess 15 so that the shank 13 will freely enter the hole 11. After the shank 13 has been pushed sufficiently far within the hole 11 that the bit 17 will be in proper position for engaging the wards of the lock, the resilience of the spring 18 will return the bit 17 to its normal position, as shown in Fig. 2, whereupon rotation of the key will result in 100 unlocking of the lock 10. When the key is withdrawn from the lock, the engagement 105 of the bit 17 with the inner face of the front wall of the lock adjacent the hole 11 will result in the bit 17 being swung into the oppo-

site position, as shown in Fig. 4 with the bit 17 disposed entirely within the recess 13. A continued pull upon the shank 13 will result in withdrawal thereof from the hole 11, after which the bit 17 will be returned to its normal position by virtue of the spring 18.

From the foregoing description and a study of the drawing it will be apparent that I have thus provided a lock and key in which 10 the formation of the key hole is such as to afford no clue as to the shape of the key in connection with the lock.

It will therefore be seen that the construction is such as to thwart any attempt 15 of an unauthorized person to ascertain the nature of the key which must be used for opening the lock.

While I have shown and described the preferred embodiment of the invention, it 20 will of course be readily understood that I may make such changes in the form, construction and arrangement of parts as will not depart from the spirit of the invention nor the scope of the subjoined claim, it being readily apparent that the construction 25 may be applied to locks of any character and not merely to padlocks as illustrated in the drawings.

Having thus described my invention I claim:—

In combination, a lock provided with a circular key hole, and a key including a cylindrical shank of a diameter to pass freely through said hole, said shank being provided at one end with a longitudinally 30 extending recess, a bit pivoted within said recess and movable to occupy a position entirely therewithin with its end extending toward either end of said shank, and a leaf spring secured at one end within said recess 35 engaging against one end of said bit for normally holding said bit in a position projecting at right angles from said shank, engagement of said bit with the lock upon insertion or removal of the shank within or from said 40 hole resulting in swinging movement of said bit to its inactive position, said spring having its free end laterally bent and engageable with the forward edge of the bit for resiliently opposing swinging movement of 45 the bit in one direction, and the spring having a bent portion adapted to engage the rear edge of the bit for opposing swinging of the bit in the other direction.

In testimony whereof I affix my signature. 50
JOSEPH B. MALYS.
